UNITED STATES PATENT OFFICE.

WILLIAM L. MURPHEY, OF SAN FRANCISCO, CALIFORNIA, ASSIGNOR TO THE CALIFORNIA WRENCH COMPANY, OF CALIFORNIA.

WRENCH.

SPECIFICATION forming part of Letters Patent No. 560,298, dated May 19, 1896.

Application filed June 21, 1895. Serial No. 553,596. (No model.)

To all whom it may concern:

Be it known that I, WILLIAM L. MURPHEY, a citizen of the United States, residing at San Francisco, in the county of San Francisco and State of California, have invented certain new and useful Improvements in Wrenches; and I do hereby declare the following to be a full, clear, and exact description of said invention, such as will enable others skilled in the art 5 to which it most nearly appertains to make, use, and practice the same.

My invention relates to that class of wrenches of the monkey type in which the fixed or stationary jaw forms a part of the shank or handle-bar of the wrench, while the movable jaw is adapted to slide upon the shank and be set at any desired distance from the stationary jaw.

My invention consists in providing the face 20 of one of said jaws with an angular sliding block or bit, which will serve as a gripping-die when the two jaws are closed upon a pipe or rod, whereby the act of turning the wrench in one direction will cause the die to slide 25 toward the pipe or rod upon the face of the jaw and increase the grip upon the pipe or rod with a force corresponding to the pressure on the handle of the wrench, while a movement of the handle of the wrench in an opposite direction will move the die in an opposite direction and instantly release the pipe or rod.

Referring to the accompanying drawings, Figure 1 is a side view of the invention. Fig. 35 2 is a side view of the same, the adjustable jaw being cut away to show the construction. Fig. 3 is a cross-section taken on the line xx of Fig. 2.

Let A represent the shank or handle-bar of 40 the wrench, and B the fixed or stationary jaw, which is preferably formed as an integral part of the shank by bending the end of the bar at a right angle and forging it to the desired shape.

C is the movable jaw, which is adapted to 45 slide upon the shank A and be fixed at any desired distance from the fixed jaw B. Usually I make opening C' in the base of the movable jaw, corresponding to the shape of the handle or shank and just large enough to 50 allow the shank to pass through it. The jaw can then be shifted on the shank, and at what-

ever point it is placed a pressure on the jaw itself will cause the shank to bind in the hole and cause a bite that will hold the jaw stationary as long as the pressure is continued. 55

Although I have shown the shank slightly serrated, as at A', on its inner side, so as to secure a more positive bite, ordinarily a smooth shank will answer every purpose.

The inner face of the movable jaw C is 60 beveled or inclined outwardly from its base toward its point, as shown in the drawings, and a triangular sliding block or die D is fitted to move freely along this inclined face. This double inclination is preferable, as will be 65 hereinafter shown; but good results could be obtained by applying a triangular sliding die-block to a rectangular face of a movable jaw.

Various means can be employed for attaching the die-block to the face of the jaw, so 70 that it will slide freely but yet be retained in place; but I have shown a round dovetail-slide arrangement—that is, I have provided the angular face of the jaw with a longitudinal round groove C². On the under side of 75 the sliding die I have provided a rib D', which fits easily in the groove. The head of the rib holds the block in place against the inclined face of the die, but the die can slide longitudinally along the face. The outer or gripping 80 face of this die is serrated in the usual way of serrating the jaws of a pipe-wrench, and if desired the gripping-face of the stationary jaw may be serrated in the same way. If now 85 these two jaws are closed upon a pipe or rod, the gripping-face of the stationary jaw will press against one side of the pipe or rod, while the gripping-face of the sliding die, which slides on the face of the movable jaw, will press it on the opposite side, and the gripping- 90 point of the sliding die will be at the base opposite its thinnest part. It will then be evident that if the wrench be turned in one direction the pressure of the pipe on the face of the movable die, combined with the rotary 95 action of the wrench, will cause the wider portion of the sliding die to move toward the pipe and bite or press it against the stationary die with a force corresponding to the rotary pressure applied to the wrench, thus making the 100 wrench an automatic or self-gripping wrench, while a slight movement of the handle of the

wrench in an opposite direction will move the angular die outward and instantly release the pipe or rod.

By setting the face of the movable jaw at 5 an angle to the handle the gripping-face of the movable die is brought more directly in line with the line of pressure against the side of the pipe and the gripping action rendered more positive. In this condition the wrench 10 will answer wherever the wrench is used with the jaws pointing downward, because in this position the weight of the sliding die will keep it thrown outward or in the open position; but if it should be used with the 15 jaws projecting upward the angular die-block would fall toward the base of the stationary jaw and render it useless as an automatic grip. To remedy this difficulty, I employ a spring E to keep it pressed out to its 20 open position. This spring can be variously applied; but I have shown a spiral spring placed in the enlargement of the slot C², so as to force the block outward and keep it in that position until the rotary pressure of the 25 pipe against the die causes it to move toward the shank. The upper end of the spring E is confined by a plate a, suitably secured to the movable jaw in the base of the opening C' thereof, as seen in Fig. 2. I also prefer to 30 have the gripping-faces of the jaws made on an incline outward, so that when their bases are brought together the faces of the two jaws will gradually recede from base to point, somewhat like the well-known "alligator-wrench." This adaptation renders it more 35 convenient. By this construction I provide

an exceedingly simple and effective pipe-wrench that can also, if desired, be used as an ordinary monkey-wrench.

I do not confine myself to the details of construction herein set forth, as it will be apparent to any mechanic that they can be varied in many ways to produce the same result in this general construction.

Having thus described my invention, what 45 I claim, and desire to secure by Letters Patent, is—

In a pipe-wrench, the combination of the stationary jaw and its handled shank, the normally-inclined movable jaw, having the 50 base of its face portion adapted to bodily impinge on said shank and said face portion inclined from said base outwardly and rearwardly toward its point, the triangular sliding block or die having an outwardly and 55 rearwardly inclined back fitting the correspondingly inclined face portion of the movable jaw, a spring to normally hold said die or block in its outer position, and a bearing-plate projecting from, and secured to, the base 60 of the face portion of said movable jaw for the inner end of said spring to hold said movable jaw, with the die or block, in the outwardly and rearwardly inclined position, substantially as set forth.

In witness whereof I have hereunto set my hand this 13th day of June, 1895.

WILLIAM L. MURPHEY.
